GUN PERFORATOR

Arthur J. Zschokke, Huntington Park, Calif., assignor to Lane-Wells Company, Los Angeles, Calif., a corporation of Delaware

Application December 8, 1941, Serial No. 422,088

8 Claims. (Cl. 164—0.5)

My invention relates to gun perforators; that is, devices adapted to be lowered within oil well casing for the purpose of perforating the casing by gunfire. Among the objects of my invention are:

First, to provide a gun perforator having a plurality of multiple bore gun units, the gun bores in each unit being in close axial arrangement and directed radially and equally spaced around the circumference of the gun body, so that the stresses incidental to discharge of the gun perforator are distributed equally around the circumference of the gun and surrounding well casing;

Second, to provide a gun perforator wherein a single conductor is sufficient for each multiple bore gun unit, thereby reducing the number of conductors required, or, conversely, increasing the number of bullets that may be fired with a given number of conductors;

Third, to provide a gun perforator which is particularly suitable for casing of small diameter, in that the gun bores may occupy a major portion of the diameter of the gun body to insure maximum muzzle velocity for a gun perforator of given diameter; and

Fourth, to provide a gun perforator wherein all of the electrical wiring is sealed within the gun body and need not be exposed at any point to well fluids.

With the above and other objects in view, as may appear hereinafter, reference is directed to the accompanying drawing, in which:

Figure 1 is a fragmentary elevational view of my gun perforator;

Figure 2 is a plan or end view of one of the gun units, indicating by differentiating dotted lines the arrangement of the several gun bores and associated elements of the gun units; and

Figure 3 is a fragmentary longitudinal sectional view through 3—3 of Figure 2, the view being taken through two annular planes.

My gun perforator comprises one or more gun bodies, designated generally by 1, which incorporate multiple gun bore gun units 2. Each gun unit includes a primary cartridge chamber 3 extending axially into the gun body from an end thereof and offset from its axis. The cartridge chamber 3 is threaded at its outer end to receive a plug 4. The plug 4 is provided with a small bore which receives a conductor 5 connected to a terminal 6 provided at the inner end of the plug 4. The inner end of the cartridge chamber 3 receives a cartridge 7 containing an explosive. The end of the cartridge adjacent the plug 4 is provided with an igniter 8 con-

taining a fuse wire adapted to be electrically connected to the terminal 6. The inner portion, or cartridge-receiving portion, of the cartridge chamber 3 is intersected by a laterally extending gun bore 9 which receives a bullet indicated by dotted lines in Figure 2. The gun bore 9 extend almost the entire diameter of the gun, its inner end projecting past the intersection with the cartridge chamber 3 and receiving an auxiliary cartridge.

Below the gun bore 9 are arranged gun bores 10 and 11, their axes preferably spaced 120° apart so that the gun bores are equally spaced around the periphery of the gun body. The three gun bores 9, 10 and 11, and associated parts, constitute the gun unit 2. The gun bores 10 and 11 are intersected, respectively, by laterally extending secondary cartridge bores 12 and 13, the cartridge bores and their respective gun bores defining planes at right angles to the axis of the gun body. The outer ends of the secondary cartridge bores 12 and 13 are closed by plugs 14, which are accessible from the exterior of the gun body. The inner ends of the secondary cartridge bores receive cartridges 1a similar to the cartridge 1, but without electrical ignition means.

Continuing axially from the primary cartridge chamber 3 is a main ignition passage 15 of small diameter. This passage is intersected by two lateral ignition passages 16, which are drilled in planes parallel to the axes of the gun bores 10 and 11, and intersect the corresponding secondary cartridge bores 12 and 13. The outer ends of the lateral passages 16 are closed by suitable plugs 17.

The gun body 1 may contain one or two gun units. If two gun units are provided, the gun body is double-ended; that is, both ends receive plugs 4, are reduced in diameter and screw-threaded. Conductor passages 18 extend from end to end of the gun body and are adapted to receive conductors for electrical connection to the lower gun unit, or to succeeding gun units in adjacent gun bodies. The gun bodies are joined together by couplings 19. Right and left threads may be provided on the couplings so that they may be rotated without necessitating relative rotation of the two adjacent gun units. Space is provided within the couplings, between the gun bodies, for the accommodation of lead wires 5a, shown by dotted lines in Figure 1. Conventional terminal means (not shown) may be provided so that the gun units may be disconnected when the couplings are unscrewed or sufficient extra lengths of wire may be accommodated within the

coupling between the gun units to permit splicing of the lead wires 5a to the conductor 5 passing through the plugs 4. If the several gun units are fired in sequence, then a single conductor is provided for each of the gun units. These conductors are suitably connected to a sequencing switch (not shown), which may be contained in a cable head 20 screw-threaded to the uppermost gun body. The cable head, in turn, is secured to a cable 21. If the gun units are fired simultaneously a single lead wire 5a is required, from which the conductors 5 branch.

Operation of my gun perforator is as follows: Upon ignition of the primary cartridge 7, by means of the conductor 5, not only is the bullet in gun bore 9 discharged, but the flame from the cartridge 7 passes through the ignition passages 15 and 16 to ignite the secondary cartridges 1a, so as to discharge the three projectiles practically simultaneously. By reason of the symmetrical arrangement of the gun bores around the gun body the forces are uniformly distributed so that there is little or no recoil to the gun. Furthermore, by reason of the equal distribution around the casing of the pressure, not only from the bullets themselves but the powder blast which follows, there is little or no distortion of the casing and the tendency to split is held to a minimum in spite of the fact that the holes are placed axially quite close together.

If it is desired to fire several units in sequence, individual lead wires connect to the several plugs 4. These leads are connected to a sequencing switch such as shown in the Johnston Patent No. 2,048,451. By means of the sequencing switch current is supplied to one gun unit at a time. If it is desired to fire all gun units simultaneously a single lead 5a is connected to all conductors 5.

Because of the compact arrangement of the gun bores and their explosive cartridges, the ignition passages are extremely short, and the total volume of these passages, compared with the total volume of the three cartridge chambers, is extremely small so that little or no pressure loss occurs. By reason of the compact arrangement of the guns and the short length of the passages, and the symmetrical arrangement of the gun bores, the guns fire virtually simultaneously, so that at no time is there any appreciable pressure differential between the several cartridge bores to create a condition wherein gases move at high velocity through the passage and cause appreciable erosion or enlargement of the ignition bores.

Various changes and alternate arrangements may be made within the scope of the appended claims, in which it is my intention to claim all novelty inherent in the invention.

I claim:

1. A gun perforator comprising: a gun body having radially directed axially displaced gun bores, a cartridge chamber having an axially extending cartridge receiving portion intersecting at least one of said gun bores, other cartridge chambers, each having laterally disposed cartridge receiving portions for the other of said

gun bores, said cartridge-receiving portions defining with their respective gun bores planes which are normal to the axis of the gun body, and ignition passages connecting said cartridge bores.

2. A gun perforator comprising: a cylindrical gun body incorporating a pair of gun units, each gun unit including a cartridge chamber intersecting an axial end of said body, laterally disposed cartridge chambers intersecting the sides of said gun body, ignition passages connecting said cartridge chambers, and a gun bore for each of said cartridge chambers; and coupling members joining a series of said gun bodies end to end.

3. A gun perforator comprising: a gun body having a cartridge chamber intersecting an axial end of said body, laterally disposed cartridge chambers intersecting the sides of said gun body, ignition passages connecting said cartridge chambers, and a gun bore for each of said cartridge chambers.

4. A gun perforator comprising: a body member defining a plurality of laterally directed gun bores, a laterally directed cartridge bore crossing each gun bore and defining therewith a transverse plane through said body member, and ignition passages interconnecting said bores.

5. A gun perforator comprising: a body member defining a plurality of laterally directed gun bores, cartridge bores intersecting said gun bores, and ignition passages interconnecting said bores; cartridges for said cartridge bores; electrical means for igniting one of said cartridges, the remainder of said cartridges being responsive to flame from said electrically ignited cartridges delivered through said passages.

6. A gun perforator comprising: a body member defining a plurality of laterally directed gun bores, cartridge bores intersecting said gun bores, and ignition passages interconnecting said bores; one of said cartridge bores extending axially and intersecting an end of said gun body, the remainder extending laterally and intersecting the side of said gun body; removable plugs for said cartridge bores; and ignition means carried by one of said plugs.

7. A gun perforator comprising: a gun body defining an axially directed cartridge bore, an ignition passage continuing axially therefrom, laterally directed cartridge bores, branch passages connecting said ignition passages therewith; and a laterally directed gun bore crossing each of said cartridge bores.

8. A gun perforator comprising: a gun body defining an axially directed cartridge bore, an ignition passage continuing axially therefrom, laterally directed cartridge bores, branch passages connecting said ignition passages therewith; a laterally directed gun bore for each of said cartridge bores; an electrically fired cartridge for said axially directed cartridge bore; and plug means closing said axially directed cartridge bore and electrically connected with said cartridge.

ARTHUR J. ZSCHOKKE.
